UNITED STATES PATENT OFFICE.

MANOEL PERRY, OF CHELSEA, MASSACHUSETTS.

BARBER'S APRON.

SPECIFICATION forming part of Letters Patent No. 371,353, dated October 11, 1857.

Application filed October 7, 1856. Serial No. 215,604. (No model.)

To all whom it may concern:

Be it known that I, MANOEL PERRY, a citizen of Portugal, residing at Chelsea, in the county of Suffolk and State of Massachusetts, 5 have invented a new and useful Improvement in Barbers' Aprons, of which the following is a specification.

The object of my invention is to provide a yoke for attachment to barbers' aprons that 10 can be readily adjusted to the wearer's neck and prevent hairs, water, or other fluids from passing down the person's neck, the yoke being also easily and readily attached to or detached from an ordinary apron.

15 The invention consists of a yoke of india-rubber or other suitable water-proof material, provided with a strap and buckle for securing it around a person's neck, and also a series of button-holes, through which buttons attached 20 to an apron are passed, thereby securing the yoke and apron together.

25 Referring to the accompanying drawings, Figure 1 represents a yoke embodying my invention, with a portion of an apron attached thereto as when worn. Fig. 2 represents the yoke laid out flat.

30 A represents the yoke, and B the apron. To one end of the yoke is secured a strap, C, and some little distance from the other end of the yoke is secured a buckle, D. The object of having the buckle thus set back is to allow the ends of the yoke to overlap when worn, as shown in Fig. 1, so that it can be adjusted to the neck of the person to which it is applied.

35 E E are button-holes cut in the yoke near

its edge, through which buttons F F, attached to the apron B, are passed, thereby securing the apron and yoke together.

It will be seen that when the apron, with its yoke, is applied to a person the yoke can be 40 readily adjusted around his neck, so as, if he is having his hair cut, to prevent any hair as it is cut off from passing down his neck, or, if he is being shampooed, prevent any water or other fluid from running down, or, if being 45 shaved, prevent the lather from passing down his neck.

The object of having the yoke detachable from the apron is, that when the latter becomes soiled it can readily be removed for washing 50 and a clean apron then be substituted.

Instead of a strap and buckle, any other suitable fastening device may be employed, and instead of buttons for attaching the apron to the yoke, hooks and eyes or any suitable 55 means may be employed.

What I claim as my invention is—

A water-proof yoke for barbers' aprons, provided with a suitable fastening device and button holes, whereby an apron can be readily 60 attached thereto or detached therefrom, substantially as shown and described.

In testimony whereof I have signed my name to this specification in the presence of two subscribing witnesses.

MANOEL PERRY.
